UNITED STATES PATENT OFFICE.

ALBERT PICK, OF CHICAGO, ILLINOIS.

DESIGN FOR A GOBLET.

43,232.

Specification for Design.

Patented Nov. 5, 1912.

Application filed September 4, 1912. Serial No. 718,580. Term of patent 7 years.

To all whom it may concern:

Be it known that I, ALBERT PICK, citizen of the United States, residing at Chicago, in the county of Cook and State of Illinois, have invented a new, original, and ornamental Design for a Goblet, of which the following is a specification, reference being had to the accompanying drawing, forming a part hereof.

This invention has for its object to provide a novel and ornamental design for a goblet.

The accompanying drawing illustrating my design is a perspective view of a goblet embodying the same.

I claim:

The ornamental design for a goblet as shown.

ALBERT PICK.
